WATERTIGHT SLIDE FASTENER CLOSURE

Ira Shur, Floral Park, N. Y., assignor to Waldes Kohinoor, Inc., Long Island City, N. Y., a corporation of New York

Application May 25, 1950, Serial No. 164,223

2 Claims. (Cl. 24—205.1)

1

This invention relates to improvements in water-tight closures for garments and the like, and more particularly to an improved slide fastener closure unit providing a positive seal against entry of liquid or moisture therethrough.

In general, it may be said that the prior slide-fastener closures designed to provide waterproofness have been either ineffective for their intended purpose or impractical. One such closure as disclosed in United States Patent No. 2,325,332 employs a double slide fastener whose fasteners are disposed in side-by-side relation, and complementary stringer tapes which are each continued to extend over (or under) a fastener. It is obvious that such a fastener is incapable of providing a positive water or liquid seal since fabric tapes are themselves not liquid- or moisture-proof and thus the expedient of covering the fasteners with fabric tapes to give waterproofness has proved ineffective, particularly in the rugged type of service encountered in the armed forces, for example. Another form of waterproof slide fastener unit employs double fasteners arranged one behind the other, with rubber sealing strips interposed therebetween. However, the overall thickness of such a closure unit is more than double that of the conventional slide fastener closure, which is an objectionable feature, and the disposition of the fasteners in directly overlying relation results in the unit having objectionable stiffness, so that it can be bent or flexed only with difficulty.

It is accordingly a principal object of this invention to avoid the aforementioned disadvantages of the prior fastener closures designed for water- and moisture-proofness, through the provision of a slide fastener closure unit which not only provides an effective liquid and moisture seal but which at the same time has an overall thickness not appreciably exceeding the thickness of a conventional single slide fastener closure.

Another important object of the invention is the provision of an improved waterproof slide fastener closure unit of the type employing two slide fasteners arranged one behind the other as above, but in which the fasteners are oppositely offset with respect to the longitudinal center line of the closure, thus to reduce the overall thickness of the unit, and wherein sealing strips disposed between the slide fasteners are so arranged and related to each other and to said fasteners that they do not materially increase the overall thickness of the unit.

A further object of the invention is the provision of a watertight slide fastener closure unit,

of the type employing two slide fasteners of more or less conventional construction, which is adapted to be attached to the edges of an opening in a garment or other article in which the unit is to be incorporated also in conventional manner, wherein sealing material is provided between the fasteners functioning hermetically to seal any opening through which liquid and moisture can possibly pass through the unit, and wherein the disposition of fasteners and sealing material is such that the overall thickness of the unit does not substantially exceed that of the conventional single slide fastener.

The above and other objects and advantages 15 of the improved watertight closure of the invention will be seen from the following detailed description thereof, taken with the accompanying drawings illustrating a preferred physical embodiment, in which:

20 Fig. 1 is a sectional-perspective view of a closure unit according to the invention shown in closed position, in which the thickness of the unit has been exaggerated for better disclosure;

25 Fig. 2 is a similar view but with the fastener opened; and

Fig. 3 is a transverse section through the closure illustrated in Fig. 1, in which the unit is shown with its normal thickness.

Referring to the drawings, a slide fastener closure unit according to the invention comprises two 30 slide fasteners designated 10 and 11, each of more or less conventional construction and differing from conventional fasteners only in the width of the fastener tapes, as will be hereinafter explained. For convenience of description, the fastener 10 will be referred to as the upper fastener and the fastener 11 as the lower fastener, but it will be understood that such designations are not intended to indicate restriction 35 in the use of the invention to any particular position of the fasteners of the unit when applied to a garment or other article.

The upper fastener 10 comprises a pair of fastener stringers whose flexible (usually fabric) 45 tapes 12 and 13 carry along their adjacent beaded edges 14, 15 rows of oppositely disposed fastener elements 16 (of which only one element has been illustrated in Fig. 1 in the interest of clarity). Said fastener elements are adapted to be engaged and disengaged in the usual manner by a slider 17 actuatable by a pull tab 18.

The lower fastener 11 similarly comprises a pair of fastener stringers whose tapes 20, 21 carry along their adjacent edges 14, 15 the oppositely 50 disposed fastener elements designated 22 which

are adapted to be engaged and disengaged by a slider 23 operated by a pull tab corresponding to pull tab 18.

According to the invention, the upper and lower fasteners are so related that their fastener openings as defined by the rows of fastener elements are oppositely offset to the longitudinal center line of the closure unit, and such offsetting is achieved in simple manner by forming the opposite tapes 12 and 21 of the respective fasteners 10 and 11 with extra width. Thus, the lefthand tape 12 of the upper fastener 10 is extra wide so that it provides, in addition to its element-attaching portion, a covering portion 24 and a garment-attaching portion 25. Similarly, the opposite (righthand) tape 21 of the lower fastener 11 has extra width such that it provides a covering portion 26 and an article-attaching portion 27.

Instead of attaching both the corresponding upper and lower tapes 12, 20 and 13, 21 of the respective fasteners to the edges of the garment or article opening, the short width or right-hand tape 13 of the upper fastener is secured to the attaching portion 21 of the lower fastener tape 21 as by a line of stitching 29, and similarly the short width tape 20 of the lower fastener is secured by a line of stitching 30 to the attaching portion 25 of the upper fastener tape 12. In this manner, the two fasteners are assembled one on the other as a unit and the unit may be attached as such to the edges of a garment or article opening in the conventional manner, as by stitching or otherwise securing the tape attaching portion 25, 27 of the upper and lower fasteners, respectively, to said edges.

With the upper and lower fasteners 10, 11 secured to one another relatively outwardly of their fastener openings, the space between the unsecured fasteners proper is completely filled with a liquid-sealing material, as indicated more particularly on an exaggerated scale in Fig. 1, and on a normal scale in Fig. 3. Such material may be, for example, natural or synthetic rubber, or some appropriate plastic material having liquid and moisture impenetrability and the requisite degree of flexibility and resiliency for use in a flexible slide fastener.

The preferred construction and attachment of the filling material is illustratively shown in Figs. 1 and 2 and comprises a pair of sealing strips 32, 33 made from a material as aforesaid, each filling approximately half of the space between the fasteners. The sealing strip 32 is secured to the under face of the covering portion 24 of the upper left fastener stringer, and the sealing strip 33 is secured to the upper face of the covering portion 26 of the lower left-hand stringer, as by a suitable adhesive. It will be observed that the width of the sealing strips 32, 33 is not substantially less than the width of the wider tape portions 24, 26 to which they are respectively attached. Such results in the strip associated with the wider tape of one fastener being disposed to cover the opening of the other fastener. The inner or adjacent edges of the sealing strips 32, 33 meet on the longitudinal center line of the closure unit, and their meeting ends 32a, 33a are complementally L-shaped so that they overlap one another. To provide intimate contact as well as large contact area between the meeting ends of the sealing strips, thus to impart thereto positive liquid- and moisture-sealing properties, said meeting ends are moreover serrated so as to provide a plurality of mating projections 32b, 33b and corresponding recesses which interfit one

with the other in the manner shown when the unit is closed.

By reference to Figs. 1 and 3, it will be further seen that the sealing strip 32 is provided in its under face with a downwardly opening channel 36 to accommodate the slider 23 of the lower fastener, and that the sealing strip 33 is provided in its upper face with an upwardly opening channel 37 to accommodate the slider 17 of the upper fastener. The channeling of the sealing strips aforesaid effects a reduction in the thickness of the closure unit and also makes for smooth operation of the sliders.

It will thus be seen that in the closed position 15 of the fasteners a closure unit of the invention is positively protected and sealed against the ingress 20 of any liquid or moisture to the article or garment through either of the openings of the fasteners 10 and 11. Moreover, due to the offsetting of the 25 fastener openings, the rows of fastener elements 16, 22 do not directly overlie one another but, instead, are oppositely offset from the longitudinal center of the closure, with the result that even with the addition of the rubber sealing strips 32, 33 the overall thickness of the fastener does 30 not substantially exceed that of a conventional slide fastener closure employing a single fastener. Hence, a liquid- and moisture-proof closure unit according to the invention satisfies the practical 35 flexibility and thickness standards required of closures adapted to be applied to garments and other articles which are themselves flexible.

It is also a feature of advantage of the illustrated closure unit that it may be readily opened 35 and reclosed, opening being simply effected as by first actuating slider 17 in fastener opening direction, whereupon the left-hand flap-like stringer 12 of the upper fastener 11 may be raised to a position generally shown in Fig. 2, thus to 40 provide access to the slider 23 of the lower fastener, which latter may now be actuated in direction as to open the lower fastener, thereby to completely separate both fasteners. The closure unit may be as simply closed by first closing 45 the fastener 1, lowering the flap-like stringer tape 12, which results in the mating serrations of the sealing strips interfitting with one another, and finally closing the fastener 10.

As many changes could be made in carrying out the above constructions without departing from the scope of the invention, it is intended that all matter contained in the above description or shown in the accompanying drawings shall be interpreted as illustrative and not in a limiting 55 sense.

I claim:

1. A self-contained closure unit for garments and the like comprising two slide fasteners assembled one on the other, each said fastener comprising a pair of companion stringer tapes carrying rows of fastener elements along their adjacent edges which define the fastener opening and a slider for engaging and disengaging said elements, a tape of one fastener and the opposite tape of the other fastener having greater width than their companion tapes whereby said fastener openings are offset laterally from the longitudinal center line of the closure unit and the opening of each fastener is covered by the wider tape of the other fastener, and sealing means completely filling the space between the two fasteners, said sealing means comprising two strips of resilient sealing material whose adjacent edges are complementally formed so as to sealingly engage one 70 with the other generally along said longitudinal

center line, each said strip being carried by the wider tape of one fastener element and having width not substantially less than the width of said wider tape whereby it also covers the opening of the other fastener, the faces of the sealing strips adjacent the fastener openings having channels for accommodating the fastener elements and sliders of the respective fasteners.

2. A self-contained closure unit as set forth in claim 1, wherein the adjacent edges of the strips are complementally L-shaped and are moreover provided with interfitting projections and recesses.

IRA SHUR.
